HIS ATTORNEY

UNITED STATES PATENT OFFICE.

ALEXANDER H. WORKMAN, OF OMAHA, NEBRASKA, ASSIGNOR, BY MESNE ASSIGNMENTS, TO THE MONARCH TYPEWRITER COMPANY, OF SYRACUSE, NEW YORK, A CORPORATION OF NEW YORK.

TYPE-WRITING MACHINE.

980,729.

Specification of Letters Patent.

Patented Jan. 3, 1911.

Application filed September 30, 1907. Serial No. 395,159.

To all whom it may concern:

Be it known that I, ALEXANDER H. WORKMAN, a citizen of the United States, and resident of Omaha, in the county of Douglas and State of Nebraska, have invented certain new and useful Improvements in Type-Writing Machines, of which the following is a specification.

My invention relates to the right-hand margin stops of typewriting machines and has for its main object to provide a single stop block with two differently located stop faces for arresting the return movement of the carriage, so as to enable the operator to indent the work and begin the lines at either of two points fixed relatively to each other, and my invention consists in the features of construction and combinations of devices to be more fully described and particularly pointed out in the appended claims.

In the accompanying drawings, Figure 1 is a sectional elevation of so much of a Monarch typewriter as is necessary to illustrate my invention, and to which style of machine my invention has been applied in practice. Fig. 2 is a fragmentary front elevation of the carriage, the longitudinal stop bar and the compound marginal stop arranged thereon.

30. In both views the same part will be found designated by the same numeral of reference.

1 designates the paper carriage which as usual in the Monarch machine comprises a back bar with top and bottom V-rails which 35 run on roller bearings 2, there being mounted on the framework opposing rails 3 having corresponding V-grooves.

Supported upon the upper rail 3 is a margin stop bar 4 formed on its front edge 40 with teeth and intermediate spaces 5 for holding the margin stop at any desired position along said bar. The compound marginal stop comprises a block 6 grooved or cut away on its underside to partially embrace the stop bar, and the block is formed with an opening for the reception and working 45 of a spring pressed catch or dog 7 for holding the block securely on said rod, one part of the catch entering one of the spaces 5 between the teeth on the bar 4, as common in the Monarch machine. The stop block is, however, otherwise differently constructed in that it is formed or provided with two stop faces or lugs 8 and 9, the lug 8 being

innermost or nearer the center of the machine and the lug 9 being outermost and longer or projecting downwardly to a greater extent than the lug 8. Both lugs are, however, in the same transverse vertical plane. Preferably both lugs are made integral with the block.

Attached to the right-hand end of the stop bar is a crank arm 10 to the rear end of which is attached a vertical connecting rod 11 whose lower end is attached to the rearwardly projecting arm 12 of a bell crank. To the upwardly extending arm 13 of said bell crank is pivotally connected the rear end of a push rod 14 provided at its forward end with a key or button 15, the forward end of the rod being mounted to slide in bearings in the framework of the machine, as indicated at 16, and a spring 15^a being provided to return these parts to normal position. The ends of the margin stop bar being mounted on pivots 17 it is adapted to be oscillated by the connections just described and for a purpose presently to be explained.

Located upon the carriage and pivoted thereto at 18 is a lever or arm 19, the upper end of which is adapted to contact with both of the stop lugs 8 and 9 to arrest the return movement of the carriage. In front of the stop member 19 is an abutment 20 for preventing the stop member from tilting toward the left when it contacts with the stops 8 and 9.

The stop member 8 is beveled on its under side as at 8^a. The distance between the vertical stop faces of the lugs 8 and 9 is preferably equal to about three letter spaces and the downward extension of the lug 9 need be far enough only to engage with the carriage stop 19 when the stop 8 is tilted upwardly to an inoperative position. The stop 8 arrests the carriage, say, at the normal marginal position. When it is desired to indent within the marginal field, the operator with one hand pushes back the margin release button 15, thus tilting the margin stop bar and raising both the stops 8 and 9 simultaneously, the stop 8 going high enough to enable the carriage stop 19 to pass by it and then to strike the inner face 105 of the lower portion of the stop 9 as the operator pulls the carriage toward the right. Thus, when desired, the carriage may be

stopped uniformly at, say, three letter space distances to the right of the normal stopping position so that the work may be indented within the marginal field at the 5 left-hand side of the sheet in this fashion:—

MCMCMCMCMCMCMCMCMCMCMCMCM
MCMCMCMCMCMCMCMCMCMCMCMCM
MCMCMCMCMCMCMCMCMCMCMCMCM
MCMCMCMCMCMCMCMCMCMCMCMCM
MCMCMCMCMCMCMCMCMCMCMCMCM

10 Of course, if desired, the two stops 8 and 9 may be fixed apart any given number of letter spaces instead of the three preferred and illustrated herein.

15 I have found in practice this construction of marginal stop to be especially useful to court reporters, authors, architects, engineers and the like, desiring to print marginal indentations within the usual fixed 20 margin at the left-hand side of the sheet.

It will be observed that the relative positions of the two stop members are fixed or unchangeable and hence the indentations may be made with uniformity and without 25 undue loss of time. Another advantage is that the two stops are adjustable bodily together without losing their relationship with respect to each other, both being mounted upon the same block and movable 30 simultaneously therewith to any desired position on the stop bar.

What I claim as new and desire to secure by Letters Patent, is:—

1. In a typewriting machine, the combination of a traveling paper carriage, a compound margin stop for arresting said carriage when pulled to the right by hand, said stop comprising a single block and two right-hand margin stops depending there- 40 from and fixed one relatively to the other

for varying the beginning of the lines of writing, the outer one of said stops depending to a lower level than the inner one, and the inner stop being beveled on its under side.

2. In a typewriting machine, the combination of a traveling paper carriage having a stop member, a margin stop bar, a right-hand margin stop block adjustable thereon and carrying two depending right-hand 50 margin stops fixed one relatively to the other for arresting said carriage when pulled to the right by hand, a dog or detent for holding said block and stops in the adjusted position, and means for tilting said stop block and stops.

3. In a typewriting machine, the combination of a paper carriage provided with a stop member, a pivotally mounted stop bar, a stop block thereon provided with two stop 60 lugs depending therefrom and having a fixed relation to each other, one of said lugs being in advance of the other and the outermost lug being the longer of the two and depending to a lower level, the carriage being 65 adapted to be arrested normally when pulled to the right by hand by the inner and shorter lug, and means for tilting the stop bar and stop lugs upward so as to enable the stopping member on the carriage to pass 70 by the inner and shorter lug and to be brought into contact with the outer and longer lug.

Signed at Omaha in the county of Douglas and State of Nebraska this 17th day of 75 September A. D. 1907.

ALEXANDER H. WORKMAN.
